CLAIM

The ornamental design for combined digital clock and thermometer with integral stand, substantially as shown.

DESCRIPTION

FIG. 1 is a front elevational view of a combined digital clock and thermometer with integral stand showing my new design;

FIG. 2 is a rear elevational view thereof;

FIG. 3 is a top plan view thereof;

FIG. 4 is a bottom plan view thereof;

FIG. 5 is a left side elevational view thereof;
FIG. 6 is a right side elevational view thereof with the stand in the open position.

FIG. 1

FIG. 5

FIG. 6

FIG. 2

FIG. 3

FIG. 4
